BRASSIÈRE

Pierre Amyot, Quebec, Quebec, Canada

Application May 8, 1947, Serial No. 746,697

5 Claims. (Cl. 2—42)

1

This invention relates to improvements in strapless brassières and has, for its principal object, the provision of a generally improved strapless brassière in which the breast pockets are arranged within a pair of arch-shaped supporting members made of cord stiffened fabric and are secured to the arch-shaped supporting members in a manner which permits free movement of the breast pockets to maintain the breasts in the correct position and to prevent undesirable tension when the brassière is drawn tightly around the body.

Other objects, advantages and characteristic features of the invention will be apparent from the following detailed description taken in connection with the accompanying drawings, in which I have shown a preferred embodiment. Referring to the drawings—

Fig. 1 is a front elevational view of my improved brassière as it appears in the flat.

Fig. 2 is a vertical sectional view taken along the line 2—2 of Fig. 1.

As shown in these drawings, my improved brassière includes a pair of breast pocket cups 5 which are preferably made of open-mesh fabric.

Each breast pocket 5 is arranged within an arch-shaped breast pocket support 6 made of cord-stiffened fabric of substantial stiffness and thickness. As here shown each arch support 6 is substantially U-shaped and is completely enclosed in a sheath 7 of a suitable facing fabric. The lower portions of the legs of each arch-shaped support 6 are connected by faggotting 9 to the ends of an interposed diaphragm band 10 having a curved upper edge 11 connected by faggotting 12 to the lower portion of the circular edge of the adjacent breast pocket 5, the remaining portion of the circular edge of the breast pocket being secured by faggotting 13 to the upper and side portions of the arch-shaped support.

The adjacent legs of the two arch-shaped breast pocket supports 6 are hingedly secured together by faggotting 15 and the outer legs of said arch-shaped supports are secured to straps 17 and 18 which are provided, at their free ends, with complementary hook and eye fasteners 19 and 20 to enable the brassière to be secured in place around the body of the wearer.

The hinge connection provided between the adjacent legs of the two arch-shaped breast pocket supports 6 and the manner in which the breast pockets are arranged within and secured to these supports and to the diaphragm bands 10 enables the breast pockets to move freely to keep the breasts in correct position and to prevent any undesirable tension which might otherwise be caused by tight adjustment of the brassière around the body. The inelastic diaphragm bands

2

10 also serve to prevent undesirable lengthwise elasticity of the front portion of the brassière and enhances the breast molding effect.

It will be noted that the arch-shaped cup supporting members 6 are transversely curved or shaped so that they extend inwardly from the edges of the breast cups 5 in such manner as to be adequately supported by the breasts when the brassière is secured in place around the body of the wearer.

Having thus described the nature of my invention and a preferred embodiment thereof, it will be understood that various modifications may be resorted to within the scope and spirit of the appended claims.

I claim:

1. A strapless brassière comprising a pair of arch-shaped breast pocket supports made of cord-stiffened fabric and arranged in side by side relation with the leg portions thereof directed downwardly, the lower portions of the contiguous legs of said supports being directly secured together by stitching, a diaphragm band interposed between and terminally secured to the lower portions 20 of the legs of each arch-shaped support and having a concavely curved upper edge, and a pair of breast pockets of circular outline each having a portion of its circular marginal edge secured to the concavely curved upper edge of one of said 25 diaphragm bands and having the remaining portion of its circular marginal edge secured to the portion of the arch-shaped support extending above said diaphragm band.

2. A brassière as set forth in claim 1, in which 35 each breast pocket is secured to the associated diaphragm band and arch-shaped supporting member by faggotting.

3. A brassière as set forth in claim 1, in which 40 the inner legs of the arch-shaped breast pocket supports are directly secured together by faggotting.

4. A brassière as set forth in claim 1, in which 45 each arch-shaped breast pocket support is completely enclosed by a sheath of facing material.

5. A brassière as set forth in claim 1, including fastening straps directly secured to the outer legs of the arch-shaped breast pocket supports.

PIERRE AMYOT.
